UNITED STATES PATENT OFFICE

2,458,140

EYE EXERCISER

Henry Breitbarth, Chicago, Ill.

Application November 21, 1946, Serial No. 711,407

3 Claims. (Cl. 128—76.5)

1

This invention relates to certain new and useful improvements in eye exercisers and the object of the invention is to provide, in a device of this character, a target, upon which the eyes are adapted to be fixed and which is designed and intended to travel an irregular course or path whereby to cause the eyes to move from left to right, thereby to exercise the various muscles of the eyes.

Another object of the invention is to provide in such a device an arrangement for illuminating the moving target upon which the eyes are adapted to be fixed during exercising, and incorporating in the circuit of said illuminating means circuit breakers whereby to momentarily deenergize the illuminating means, preferably at a time simultaneously with the passing of the target in close proximity to the illuminating means, thus momentarily causing loss of view of the target at the time that the illuminating means becomes deenergized so as to compel the user to employ the eyes to relocate the target, thereby exercising the eyes.

Another and equally important object of the invention is to provide an eye exercising device which will be simple in construction, easy of operation and economical in manufacture.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a suggested cabinet for enclosing the mechanism embodied in my eye exercising device;

Fig. 2 is a cross sectional vertical detail view of the same taken approximately on line 2—2 of Fig. 1;

Fig. 3 is a schematic detail view of a suggested circuit to be embodied in my invention; and

Fig. 4 is a horizontal sectional detail view of the invention taken approximately on line 4—4 of Fig. 2.

In carrying my invention into effect and to accomplish the several objects thereof, I provide a suitable cabinet 10 comprising a bottom wall 11, front and back walls 12 and 13, and side walls 14. The cabinet further includes a top wall 15 preferably formed integral with the front wall 12 and removable with the latter wall to afford access to the interior of the cabinet 10.

A sight opening 16 is preferably surrounded by an eye shield 17, the front edge 18 of which is

2

curved to afford comfort when the user places his head against the shield 17 in positioning the eyes for viewing through the opening 16.

Within the cabinet 10 and on opposite confronting faces of the side walls 14 are mounting brackets 19, which support a mounting plate 20. On this mounting plate 20 are arranged vertically extending shafts 21, with certain of these shafts 21 positioned with respect to each other so as to move a chain 22 through an irregular path and to form the medial portion of the chain 22 in substantially the form of a triangle in plan view, with the apex of the triangle substantially positioned in alignment with a vertical center line 15 through the sight opening 16. The remaining of these shafts 21 direct the opposite portions 23 of the chain 22 in an elongated path away from the medial portion of the chain 22.

Each of these shafts 21 has operative connection with the chain 22 by suitable sprocket gears 24. It is desirable that the chain 22 be substantially taut so as to prevent irregular movement thereof, or vibration during its travel over the sprocket gears 24, thus maintaining the target 25 in an upright position. For this purpose, any suitable tightening device may be provided. Such tightening device has not been illustrated nor described because it does not in itself constitute any part of the present invention.

One of the shafts 21, such as indicated at 25, extends below the mounting plate 20, and on the shaft indicated at 25 there is mounted a gear 26 having operative meshing relation with a worm gear 27 mounted on a shaft 28 of a motor 29 supported by and attached to the bottom wall 11 as at 30.

Carried by the chain 22 as at 31 is a post 32, the upper end of which carries a target 33. This target 33 is shown in the form of a ball and is preferably provided with a color not injurious to the eyes by reason of brightness. The target 33 may be of any suitable shape other than a ball which will best serve the purpose.

Carried by the side wall 14, adjacent the side loops 34 of the chain 22, are mounting brackets 35, each supporting a socket 36, into which is threaded an electric lamp bulb 37.

In Fig. 3 I have illustrated a suggested circuit for the motor 29 and the electric bulbs 37. In this circuit there is a master control switch 38 and a rheostat 39 regulating the speed of operation of the motor 29. There is also incorporated in this circuit switches 40 for controlling the circuit to the electric bulbs 37, and it is intended that there depend from the chain 22 lugs 41

adapted to engage elements 42 of each of the switches 40, whereby to deenergize the electric bulbs 37 simultaneously with the passing of the target 33 in front of the bulbs 37. The circuit illustrated in Fig. 3 is connected in source with the power line through the medium of a suitable plug 43.

To complete the invention, a suitable means may be employed to support the cabinet 10 at an inclination with respect to the horizontal to afford convenience of use.

In the use of the apparatus, the user positions his head with respect to the shield 17 so that he may have a view through the sight opening 16. The switch 38 is closed to start the operation of the motor 29, the speed of which is regulated by the rheostat 39. The user will locate the target 33 and keep his eyes fixed thereon. Assuming that the target 33 starts at the point A and that the chain 22 is moving in the direction of the arrow (Fig. 4), it will be noted that the target 33 will move away and to the left of the sight opening 16 and then take a course directly parallel with the front wall 12 of the cabinet and return in that parallel path to a point where the target 33 then moves toward the user to the apex of the triangle defining the path of movement of the target 33, which is the point A. From this point, the target 33 then travels in a similar path but to the right of the line of fixation, as viewed in Fig. 4. Each time the target passes in front of the electric bulbs 37, these bulbs 37 are deenergized so that momentarily the target 33 is lost to the user but upon energization of the bulbs 37, the target is then easily located. Thus, the muscles of the eyes may be exercised as well as the pupils thereof.

Against the inside face of the front wall 12 may be placed a suitable mirror 12' for reflecting the light back into the cabinet.

While I have illustrated and described the preferred form of construction for carrying my invention into effect, this is capable of variation and modifications without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An eye exercising device comprising a target, means for moving said target along an irregular path, said path comprising a medial portion of

substantially triangular formation in plan view, with the apex of the triangular path nearest the position of the user of the device, means for controlling the movement of said target moving means, illuminating means at certain points of travel of said target along said path, and means for momentarily deenergizing said illuminating means as said target is moved by said target moving means past said illuminating means.

2. An eye exercising device comprising a cabinet having a sight opening formed in a wall thereof, an eye shield surrounding said opening, a mounting plate in said cabinet, a continuous chain, sprocket gears supported by said mounting plate and having operative engagement with said chain for moving said chain through an irregular path substantially in parallel spaced relation with respect to the mounting plate, with the medial portion of said path forming substantially a triangle in plan view with the apex of the triangle adjacent the sight opening, means acting upon one of said sprocket wheels for moving said chain, and a target carried by said chain.

3. An eye exercising device comprising a cabinet having a sight opening formed in a wall thereof, an eye shield surrounding said opening, a mounting plate in said cabinet, a continuous chain, sprocket gears supported by said mounting plate and having operative engagement with said chain for moving said chain through an irregular path substantially in parallel spaced relation with respect to the mounting plate, with the medial portion of said path forming substantially a triangle in plan view with the apex of the triangle adjacent the sight opening, means acting upon one of said sprocket wheels for moving said chain, a target carried by said chain, said chain from the base of said triangular path adapted to travel in a straight line laterally from said triangular path, illuminating means at the end of said latter path of movement of the chain, and means for deenergizing said illuminating means as said target is moved by said chain past said illuminating means.
